R. J. GIBBONS.
Railroad Tank-Feeders.

No. 140,132.

Patented June 24, 1873.

Inventor.

Richard J. Gibbons

UNITED STATES PATENT OFFICE.

RICHARD JOHNSON GIBBONS, OF ST. LOUIS, MISSOURI.

IMPROVEMENT IN RAILROAD-TANK FEEDERS.

Specification forming part of Letters Patent No. 140,132, dated June 24, 1873; application filed November 22, 1872.

To all whom it may concern:

Be it known that I, RICHARD JOHNSON GIBBONS, of the city and county of St. Louis and State of Missouri, have invented a new and useful Improvement in Devices for Pumping Water for Railroad-Tanks and other purposes by the Locomotive; and do declare the following to be a full, exact, and complete description of the same, referring by letters to the accompanying drawing.

Figure 1 represents a plan of the machine or apparatus embodying my invention. Fig. 2 is an elevation of the same.

A A shows two horizontal beams placed in the center of the railroad track, parallel with the rails b b, and extending each way from the main shaft C and the small shaft e. These beams are made of iron or wood; and, if wood, iron cog-plates should be securely fastened to the under side. These beams are placed on rollers and guides to allow them a reciprocating motion over the cog-wheels e e. A rubber plate or spring, d, is fastened on the ends of these beams to prevent jarring when the locomotive is brought in contact with them.

I do not confine myself to any particular size or length of beams, as they can be made of any size or length corresponding with the work for which they are intended.

These beams are then brought in contact with the locomotive by means of a drop-lever on the locomotive under the control of the engineer, and made to pass over the wheels e e, revolving the shaft C and its wheel B in the cogs on the weight-shaft h, and thus elevating the weight as high as the beams will permit. The shaft C is connected to the weight-shaft at one end, and the beams at the other. The large wheel E is placed on the main shaft, and communicates the power of the descending weight to a smaller wheel, f, and to a pump. This wheel can be made of iron or wood, and with cogs on its circumference, or can be run by a belt. This wheel revolves but one way,

and is prevented from turning, when the weight is wound up, by the pawl I. A fly or balance wheel can be placed on the small wheel f to control its motion. The size of the wheel E is governed by the size of my invention and the time the pump is intended to work. The weight is contained in the box G, filled with rock or stone, and supported on the weight-shaft h and the frame K. The shaft is guarded by rollers or guides to prevent friction and allow it to rise and descend easily.

The beams can be replaced by the descending weight while the pump is working, or can be replaced by means of a spring for that purpose. The pipe conveying the water to the tank, and of the pump, can be of any size, depending entirely on the amount of water used by locomotives, the amount in the stream or well, and the size of the pump used at that place. The length of time the pump will work is governed by the length of the beams, the height of the weight, the amount of weight used, and the size of the wheel E.

I do not confine myself to any particular dimensions, as before stated, as the size and proportions of the apparatus may be varied without departing from my invention.

In this way I am able to use the power of the locomotive for pumping water for railroad tanks and other purposes, if desired.

What I claim as new, and desire to secure by Letters Patent of the United States, is—

The rack-beams A A, shafts C and e, the former provided with the wheels B and E and cog e, and the latter with wheel B and cog e, in combination with the wheel f, weight-shaft h, and weight G guided in the frame K, when operated by a passing locomotive, substantially as and for the purpose hereinbefore set forth.

RICHARD JOHNSON GIBBONS.
